C. A. Snowdon

UNITED STATES PATENT OFFICE.

SAMUEL H. RADWAY, OF BERLIN, WISCONSIN.

WINDMILL.

SPECIFICATION forming part of Letters Patent No. 349,742, dated September 28, 1886.

Application filed April 19, 1886. Serial No. 199,401. (No model.)

To all whom it may concern:

Be it known that I, SAMUEL H. RADWAY, a citizen of the United States, residing at Berlin, in the county of Green Lake and State of Wisconsin, have invented a new and useful Improvement in Windmills, of which the following is a specification.

My invention relates to improvements in windmills; and it consists of the peculiar and novel construction and combination of parts, substantially as hereinafter fully set forth; and specifically pointed out in the claim.

The object of my invention is to overcome the serious objection that exists in a number of "geared" windmills which are liable to be thrown out of the wind when the vertical shaft thereof encounters resistance and strain in setting the machinery in motion that it is designed to drive; and, further, to simplify the construction of the mill and thus also cheapen or lessen the cost of the manufacture while at the same time the parts shall be strong and durable and effective in operation.

In the accompanying drawings, Figure 1 is a front elevation of a windmill embodying my invention, the tower and arms of the wheel being partly broken away. Fig. 2 is a top plan view thereof. Fig. 3 is a side elevation of my improved mill.

Referring to the drawings, in which like figures of reference denote corresponding parts in all the figures, 1 designates the tower of the windmill, a portion only of which is shown, and which is of the ordinary or any preferred construction; and 2 the turn-table that is rotatively mounted or journaled on the tower to adapt it to revolve with the wheel and other devices or mechanisms which it carries. The table extends down into the tower, and it bears on a bridge-tree, 3, at its lower end, and by which it is supported, and this bridge-tree is secured rigidly in place in the tower by means of inclined integral lugs 4, that bear against the inner faces of the tower to adapt through-bolts 5 to pass through the lugs and tower, as will be very readily understood. The bridge-tree 3 is further provided at its middle with an opening, 6, for the passage therethrough of bolts or straps 7, to secure a cap-plate, 8, to the lower end of the turn-table 2. The lower end of the turn-table bears on the

bridge-tree around the opening 6 therein and the cap-plate 8 bears against the lower face of the bridge-tree, to prevent the turn-table from being elevated out of and carried away from the tower by the high winds, the straps or bolts 7 and cap-plate 8 being carried by the turn-table in its movements. The upper end of the turn-table is provided with an outwardly-flared circumferential edge, 10, which bears in the curved inner edge of a socket-plate, 9, that is bolted directly to and supported by the windmill-tower 1.

11 designates the wind-wheel, which is arranged to one side of the tower and the turn-table thereon, and the wheel is of any preferred construction. The wheel is provided with a central hub, 12, that is rigidly secured or keyed on a shaft, 13, a series of radial arms, 14, and a ring or annulus, 15. The inner ends of the arms are secured in the hub, and they may be braced and strengthened in any preferred manner, and carry blades of suitable construction. The ring or annulus is arranged concentric with the hub, and is of considerably larger size, and at its periphery it is provided with a series of perforated lugs, 16, which bear against the radial arms, and are secured thereto to brace and strengthen the same by through-bolts 17, while on the inner edge the ring is provided with a series of teeth or cogs, thus adapting it for use as a circular rack. The shaft 13 of the wind-wheel is arranged on one side of the center of the turn-table, and supports the wheel thereon out of the axial line of table, and the shaft is journaled in suitable boxes or bearings, 17', that are rigidly secured to and carried by the turn-table. A counter-shaft, 18, is arranged parallel with the wind-wheel shaft 13 and with the axial line of the turn-table, and the said counter-shaft is elevated above the wind-wheel shaft, and journaled in bearings 19, that are supported by standards 20, which are secured to the turn-table and carried thereby. Suitable collars are secured on the wind-wheel and counter-shafts to prevent longitudinal play thereof in their respective bearings, or other equivalent devices may be employed for effecting the same result; and at one end the counter-shaft is provided with a pinion, 21, that meshes with and is rotated by the circu-

lar rack 15' of the wind-wheel 11, the pinion being arranged within and eccentric with the periphery of the said ring or rack. At its middle, or thereabout, the counter-shaft carries a bevel gear-wheel, 22, that is rigidly secured or keyed thereon, and the bevel gear-wheel meshes with and rotates a smaller bevel pinion, 23, that is arranged to rotate in a plane at right angles to the plane of the wheel 22.

10 The bevel-pinion is rigidly secured on a vertically-disposed shaft, 24, that extends through the tower and the turn-table thereof, and the said pinion 23 is secured on the vertical shaft above a bridge-tree, 25, which is arranged across the central opening in the turn-table, and is bolted at its ends to the turn-table, and is carried thereby in its rotatory movements. The bridge-tree supports the vertical shaft at its upper end, and the shaft is used to drive 20 the machinery of any class, and the turn-table rotates around the vertical shaft without affecting the latter. The vane or tail 26 is rigidly secured to the turn-table by bolts or otherwise, and the vane is arranged on the opposite side of the tower to the wind-wheel. The vane is arranged on the opposite side of the counter-shaft to the wheel-shaft, and it is inclined to the said counter and wheel shafts or disposed diagonally with relation thereto, as 25 clearly shown in the plan view, Fig. 2, of the drawings. By thus arranging the wind-wheel shaft out of the usual line of the turn-table, I utilize the force of the wind thereon to counterbalance or equalize the strain on the vertical shaft that is caused and due to the resistance of the machinery to be operated, whereby 30 the resistance of the machinery is overcome and obviates the serious objection of throwing the wheel out of the wind. The vane being arranged on the opposite side of the counter-shaft to the wind-wheel shaft, also aids in securing the above desired result, and the vane is braced and strengthened by tie-rods 27, that are bolted thereto at one end, and at their 35 opposite ends they are secured to lugs 28, on opposite sides of the turn-table, by suitable nuts. When the wheel rotates, it carries with it the circular rack, which drives with it the pinion and the counter-shaft, and the bevel 40 gear-wheel of the latter shaft rotates the bevel-pinion and the vertical shaft that drives the

machinery, and when the wind shifts or changes the vane turns the wheel to keep it in the wind, and the turn-table also rotates with the wheel and carries with it the various shafts and 55 journal-bearings.

The operation of my invention will be readily understood from the foregoing description taken in connection with the drawings.

I do not confine myself to the exact details 60 of construction and form and proportion of parts herein shown and described as an embodiment of my invention, as I am aware that changes therein can be made without sacrificing the advantages of my invention. 65

I attach especial importance to the shaft journaled on a turn-table and arranged to one side of the axial line thereof, and carrying a wheel and a rack, a counter-shaft also journaled on the turn-table parallel with the wheel-shaft and having a pinion meshing with the rack, and a regulating-vane also carried by the turn-table and arranged at an angle to the wheel and counter shafts, and on the opposite side of the counter-shaft to the wheel-shaft, as 70 75 therein lies the gist of my invention, whereby the resistance and strain on the parts experienced in setting the machinery in motion which the wheel is designed to operate, is entirely overcome.

Having thus fully described my invention, what I claim as new, and desire to secure by Letters Patent, is—

In a windmill, the combination of a turn-table, a shaft carrying a wheel and a rack, 85 journaled on the table and arranged to one side of the axial line thereof, a counter-shaft also journaled on the turn-table and geared with the rack of the wheel-shaft, and arranged parallel therewith, a vertical shaft geared to 90 the counter-shaft, and a regulating-vane affixed to the table diagonally to the wheel and counter-shafts, and on the opposite side of the counter-shaft, substantially as described.

In testimony that I claim the foregoing as 95 my own I have hereto affixed my signature in presence of two witnesses.

SAMUEL H. RADWAY.
